UNITED STATES PATENT OFFICE.

WILLIAM NEWTON BEST, OF LOS ANGELES, CALIFORNIA, ASSIGNOR TO
W. N. BEST INTERNATIONAL CALORIFIC COMPANY, OF LOS ANGELES,
CALIFORNIA, A CORPORATION OF CALIFORNIA.

FURNACE.

SPECIFICATION forming part of Letters Patent No. 761,624, dated May 31, 1904.

Original application filed June 9, 1902, Serial No. 110,921. Divided and this application filed September 4, 1903. Serial No. 171,938. (No model.)

To all whom it may concern:

Be it known that I, WILLIAM NEWTON BEST, a citizen of the United States, residing at Los Angeles, in the county of Los Angeles and 5 State of California, have invented new and useful Improvements in Furnaces, of which the following is a specification.

This invention relates to a furnace for heating locomotive and stationary boilers and for 10 other purposes.

The invention is peculiarly applicable to furnaces for burning liquid fuel, but is not limited thereto, being also adapted for furnaces in which solid fuel is burned.

15 This invention pertains to the construction and formation of the fire-box and the adjuncts thereto for accomplishing the objects herein specified.

While the invention is applicable to various 20 kinds of furnaces, it is specially adapted for the furnaces of locomotive-engines.

In some furnaces it is necessary to line the fire-box with fire-brick or some other refractory material. Heretofore great difficulty 25 has been experienced in holding the fire-brick in the fire-box, especially on high-speed passenger-engines. An object of this invention is to overcome this difficulty. This I do by using foundation-brick of peculiar construction, 30 provided with lugs or shoulders at the top in order to hold in place the superposed bricks, and said superposed bricks may be constructed with tongue and groove in order to hold them in place, and may be further 35 supported by lugs or studs fastened to the shell of the fire-box.

The requirements of railways are such that 40 locomotives should be capable of doing service on either freight-trains or passenger-trains; and an object of this invention is to provide means whereby the furnace for the locomotive may be readily changed from passenger service to freight service, and vice versa.

Another object of the invention is to secure 45 a high degree of efficiency in the consump-

tion of the fuel and the application of the heat where required.

Another object of this invention is to provide means whereby the fire-box of the furnace can be so lined with refractory walls that 50 the flame may be directed against the walls and recoil under an arch and all portions of the fire-box may be filled with flame, guarding against uneven expansion and distributing the heat evenly in all portions of the fire-box, 55 as well as to and through the flues.

In order that perfect combustion may be obtained, I have provided superior means for admitting air into the furnace or fire-box at a novel and highly-desirable point in addition 60 to the points at which the air has heretofore been admitted, and thus to provide the necessary oxygen and in a measure superheat the same to insure the desired perfect combustion.

In this invention air may be admitted at 65 various advantageous parts of the fire-box or furnace.

It is well known that the cross-wall and arch-brick of an oil-burning locomotive-furnace is liable to waste away, owing to the excessive heat. An object of this invention is to prevent this wasting away of such wall and arch. This I do by making the same hollow and passing air therethrough, and at the same time I increase the efficiency of the furnace 70 by introducing said air to the blaze in a superheated condition at such a place as to increase the combustion over what would otherwise occur.

Owing to the peculiar construction and different types of locomotive fire-boxes, which render necessary a varied construction of linings and arch-brick and fire-brick, I do not limit myself to any particular type or construction, keeping within the limits of construction of 85 the fire-box and lining practically, as herein-after described, varying in size and construction to meet the demands of different types of locomotive fire-boxes.

Another object of the invention is to pro- 90

vide a fire-brick lining for the fire-boxes of locomotives which can be easily placed in position and taken apart and replaced and repaired.

5 Although I have shown and described a structure peculiarly adapted to the burning of liquid fuel, yet certain of the elements of said structure can be dispensed with and the remaining elements usefully employed in furnaces provided with grates.

10 The accompanying drawings illustrate the invention.

Figure I is a fragmental view of a locomotive furnished with my invention. Fig. II is a sectional plan of the same. Line II II in Fig. I indicates the lines of sight from which the view is taken, the sides being sectional below the swell of the fire-box. Dotted lines indicate parts of the construction obscured from view by other parts. Fig. III is an enlarged detail of portions of the bottom lining and dampers attached shown in Fig. I. Fig. IV is a broken plan detail of one of the side walls of the fire-box and lining therefor. The shell 15 of the fire-box is shown in section. Fig. V is a section on line V V, Figs. I and II. Fig. VI is a fragmental detail rear elevation omitting the fire-box and the ash-pan and showing the arrangement of the dampers for closing 20 the front air-passage from the ash-pan or air-trunk into the fire-box. The oil-burner is also shown as in place. Fig. VII is a perspective view of one of the foundation-bricks detached. Fig. VIII is a perspective of one of 25 the superposed wall-bricks detached.

30 1 designates the fire-box; 2, an air-trunk beneath the same, which corresponds to the part ordinarily called the "ash-pan" in coal-burning locomotives. The same is closed from end to end and open at its ends, said open ends being provided with dampers 3 and 4, respectively, for regulating the flow of air into the air-trunk from either or both ends.

35 5 is an arch in the fire-box.

40 45 6 is a bottom lining beneath the fire-box and over the air-trunk 2.

7 is an air-passage the walls of which are imperforate, extending from the air-trunk into the fire-box at the cross-wall 8 at the front 50 end of the fire-box. The passage 7 is unbroken and continuous, its walls being imperforate, so that by the time the air is discharged therefrom and introduced to the blaze it is thoroughly heated.

55 59 designates means for regulating the size of the air-passage 7. Any suitable means may be provided for this purpose. In the drawings the same consists of an adjustable plate held in place by a stud and nut 10.

60 60 11 is an air-passage leading from the rear end of the air-trunk into the fire-box below the oil-burner 12.

13, 14 designate two adjustable plates which constitute means for regulating the size of the

air-passage 11, and thus control the flow of air into the fire-box at the rear end thereof.

15 designates bolts and nuts working in slot *j* for this purpose. A suitable support is provided for the bottom lining 6. Such support may be angle-irons 16, fastened to 70 the side sheets of the shell 17 of the fire-box, and a plate 18, resting on said angle irons or brackets 16.

19 designates foundation-bricks carried by said supports 16 and 18, and the same are held 75 in place by the bricks *a* of the bottom lining 6, said bricks being fitted between said side foundations 19. Each of the foundation-bricks is shouldered at the top, the shoulder 20 being desirably constructed along the inner 80 edge of said foundation-bricks 19, leaving a sufficient space between said shoulder and the shell 17 of the fire-box to allow the wall-bricks 21 and 22 to fit snugly between the shoulders 20 and the shell 17.

85 23 is a wedge-brick to fit beneath the section *b* of the arch to give the arch a proper and uniform pitch. The wall-bricks 21, which are rearward of the arch, may be taller than the wall-bricks 22, which form the piers of 90 the arch, so that when the bricks are in place, as shown in Fig. I, the wedge 23 is firmly held against rearward movement. The arch-sections are formed integrally of suitable refractory material and may be beveled to correspond with the slant of the wedge, so that when the wedge is in place on the front wall-bricks 22 gravity will act to hold the arch-sections *b* from rearward displacement.

95 24 designates grooves, and 25 tongues on the 100 wall-bricks 21. The rear ends of the wall-bricks 22 and of the wedge 23 are provided with corresponding grooves 24 to receive the tongue 25 of the foremost of the wall-bricks 21.

26 is a stud in the shell of the fire-box to 105 enter the groove 24 of the rearmost of the bricks 21.

27 is an angled stud projecting from the side wall or shell of the fire-box to enter a groove 24 in the foremost of the bricks 21. An intermediate one of the bricks 21 may be provided with a notch 20 to receive the angled or headed stud 27. The head of said stud is designed to project into line with the tongue 25 of said brick when said brick is brought into 115 position. The notch 28 will be at the appropriate height to receive the stud 27 when the intermediate brick 21 is brought into position on the foundation-bricks or members 19.

29 is the cap-piece of the cross-wall 8 at the front end of the arch and of the fire-box. The same may be constructed of standard fire-brick or may be of larger brick, as shown.

30 is an air-passage extending up from the air-trunk 2 through the cross-wall 8 and cap 29 and through the members or sections *b* of the arch and opening at the rear end of the arch, so that the cross-wall and the arch are hollow

and air may be admitted to the flame as it bends around the arch, thus giving oxygen at this point beneath the flame to complete the combustion. The air passing through the 5 heated cross-wall and arch-sections will prevent the superheating of said wall and sections and will become itself highly heated before coming into contact with the flame, so that the walls and arch-sections will be protected from the destructive action of the fire and the oxygen will be introduced to the flame in the most effective manner and condition for completing combustion.

In practical construction of the fire-box, 15 the shell and the support 18 being in place, the foundations 19 will be placed in position and the members *a* of the bottom lining 6 will be placed on the support between the foundation-pieces 19. The cross-wall 8 will 20 be built then at the sides of the fire-box. The arch-wall bricks 22 will be placed in position on the foundation-pieces 19. Then the intermediate wall-bricks 21^b will be brought into 25 position on the foundation-bricks 19 rearward of the studs 27 and will be slid on top of the foundations 19 until the studs 27 enter the notches 28, whereupon the heads of said studs project into the line of the tongues 24 of said bricks 21^b. Then the foremost and rearwardmost of the wall-pieces 21 will be slid vertically down into place, the one entering the space between the piece 21^b and the rearmost of the arch wall-bricks 22, while the rearmost of the wall-pieces 21 will be inserted 30 between the intermediate wall-pieces 21^b and the rear sheet or shell *c* of the fire-box. The arch-wedges 23 may then be slid vertically down into place and the arch-sections *b* placed upon said wedges 23. 35 31 designates a combustion-chamber with closed bottom for use on large locomotives having long fire-boxes. The same is between the front end of the arch 5 and the outlet 32 from the fire-box. In short fire-boxes this 40 combustion-chamber may be dispensed with, as may also one section of the arch, thus to give sufficient space between the arch and the back sheet *c* of the fire-box.

It is very important that the air-inlets 7 and 11 from the air-trunk 2 be regulated to supply the air according to the requirements of the service. This will be done by loosening the nuts 10 or 15, as the case may be, and sliding the plates 9 or 13 14 to the appropriate adjustment. The dampers 3 and 4 at the rear and front ends of the air-trunk are under the control of the engineer by means of connecting-rods 33 and 34, respectively, portions of which are shown in the drawings. 45 The air-trunk 2 extends or spreads under the entire bottom of the bottom lining 6 and is of considerably-greater cross-sectional area than the passage opening at the rear of the arch.

In practical operation it will be found necessary to close the damper at the end of the air-trunk toward which the locomotive moves—that is to say, when the locomotive is going forward the damper 4 will be closed and the damper 3 opened, and vice versa when the motion of the locomotive is reversed.

Each of the arch-sections *b* may be in the form of an arc *d* and combined springer and pier portions *e* at the ends thereof, all in a single piece, and the lower ends or faces of the combined springer and pier portions *e* will desirably be equal in width to the top of the wedge-sections 23, respectively, so that there will be no opening or projection where the fire may act destructively upon the material of the sections or wedges where they come in contact with each other.

When the arch-sections *b* are not of sufficient length to span the space between the side sheets of the fire-box, I fill in the space 85 between said side sheets and the ends of said arch-sections with what is known as "grog"—i. e., a mortar formed of fire-clay and sand to hold the arch-sections in place. *g* designates such grog.

It is to be understood that one or more arch-sections may be used without departing from the principle of this invention.

This application is a division of my application filed June 9, 1902, Serial No. 110,921. 95

What I claim, and desire to secure by Letters Patent of the United States, is—

1. An elongated fire-box having an arch, foundation-bricks extending along the sides of the fire-box under and behind said arch, 100 and tongue-and-groove bricks mounted on said foundation-bricks and fitted together.

2. An elongated fire-box comprising a shell, a support fastened to the shell, a series of wall-foundations on said support, means for holding the wall-foundations in place, said series extending lengthwise along the opposite sides of the fire-box having shoulders at the top opposite the shell, and superposed bricks held in place between the shoulder and the 110 shell.

3. A fire-box lining comprising side pieces of different heights fitted in place; wedge-pieces on the lower side pieces and engaging the taller side pieces and one or more arch-sections on the wedge-pieces. 115

4. A fire-box lining comprising interlocking side pieces of different heights; wedge-pieces on the lower side pieces and engaging the taller side pieces, and one or more arch-pieces on the wedge-pieces. 120

5. A fire-box having a lining comprising grooved interlocking members and studs hooking into said grooves of said members and fastened to the shell of the fire-box. 125

6. A fire-box having studs in side and rear sheets and tongue-and-groove lining members which are fitted together, an intermediate one

of said members being furnished with a notch to receive one of said studs, and said stud being headed and engaging in a groove of another section.

5 7. An integral fire-box arch-section comprising an arc and combined pier and springer portions at the ends thereof.

In testimony whereof I have signed my name

to this specification, in the presence of two subscribing witnesses, at Los Angeles, in the county of Los Angeles and State of California, this 29th day of August, 1903.

WILLIAM NEWTON BEST.
